UNITED STATES PATENT OFFICE.

CHARLES BEURGAN SLOCUM, OF QUINCY, ILLINOIS.

SANDAL.

1,142,854.

Specification of Letters Patent. Patented June 15, 1915.

Application filed August 27, 1914. Serial No. 858,979.

To all whom it may concern:

Be it known that I, CHARLES B. SLOCUM, a citizen of the United States, residing at Quincy, in the county of Adams and State 5 of Illinois, have invented new and useful Improvements in Sandals, of which the following is a specification.

This invention relates to sandals and consists in certain improvements in the construction thereof as will be hereinafter fully described and pointed out in the claims.

The sandal is especially designed for use with shoes in places such as ice cream factories where the sloppy conditions of the 15 floor make it desirable to lift the sole of the shoe above the floor.

The invention is illustrated in the accompanying drawings as follows:

Figure 1 shows a vertical longitudinal 20 section through the center of the sandal. Fig. 2 a plan view.

The sandal is formed of a rear part 1 and a fore part 2. These are preferably formed of wood. They are joined by a hinge 3 preferably arranged just back of the ball of the foot. The hinge has a pintle 4 near the upper surface of the sandal and leaves 5—5 extend downwardly between the parts 1 and 2. At the bottom of the sandal the leaves 30 are bent and have the extensions 6—6 extending to the front and rear of the joint. These extensions are secured to the bottom of the sandal by round headed screws 7 forming projections or lugs to prevent slipping. A heel guard 8 is provided to which the securing straps 9 are secured and the strap 10 is secured to the fore part. A protecting plate 11 is arranged on the heel giving the heel a wearing surface. The articulated structure of the sandal tends to give 40 to the parts front of and back of the joint a slight longitudinal movement as the joint is flexed. This tends to wear the bottom of the sole of the sandal. With the present 45 construction the leaves of the hinge are uti-

lized to take this wear and at the same time make a more secure fastening of the hinge with the parts of the sandal. Headed fastening devices are preferable in that they not only secure the hinge leaves to the sandal but prevent slipping.

What I claim as new is:—

1. A sandal comprising a fore part, a rear part, and a hinge joining said parts, the axis of the hinge being near the top of the sandal and the leaves of the hinge extending downwardly between the parts, the forward leaf 55 extending forwardly forming a wearing surface for the bottom of the fore part of the sandal.

2. A sandal comprising a fore part, a rear part, a hinge joining said parts, the axis of the hinge being near the top of the sandal and the leaves of the hinge extending downwardly between the parts, the forward leaf 65 extending forwardly forming a wearing surface for the bottom of the fore part of the sandal, and fastening devices for securing the forwardly extending part of the leaf 70 to the fore part, said fastening devices extending downwardly from the surface of the leaf.

3. A sandal comprising a fore part, a rear part, and a hinge joining said parts, the axis of the hinge being near the top of the sandal and the leaves extending downwardly between the parts, the forward leaf 75 extending forwardly along the bottom surface of the fore part and the rear leaf extending rearwardly along the bottom of the rear part forming a wearing surface for the bottom of the sandal adjacent to the joint.

In testimony whereof I have hereunto set my hand in the presence of two subscribing witnesses.

CHAS. BEURGAN SLOCUM.
